CLAIM

The ornamental design for a case, as shown and described.

DESCRIPTION

FIG. 1 is a left side elevational view of a case showing my new design;

FIG. 2 is a right side elevational view thereof;

FIG. 3 is a front elevational view thereof;

FIG. 4 is a rear elevational view thereof;

FIG. 5 is a top plan view thereof;

FIG. 6 is a bottom plan view thereof; and,

FIG. 7 is a perspective view thereof.

The broken lines illustrate portions of the case and form no part of the claimed design.
